UNITED STATES PATENT OFFICE

NORMAN H. SAUNDERS, OF HOMEWOOD, AND CLARENCE E. LOMAX, OF OAK PARK, ILLINOIS, ASSIGNEES TO RESERVE HOLDING COMPANY, OF KANSAS CITY, MISSOURI, A CORPORATION OF DELAWARE

TELEPHONE SYSTEM

Application filed April 16, 1928, Serial No. 270,198. Renewed September 15, 1930.

The present invention relates to telephone systems in general, but is concerned more particularly with semi-automatic telephone systems, and the main object, broadly stated, is the production of a semi-automatic telephone system wherein a common group of senders may be used by semi-automatic operators in a centralized exchange in setting up connections from local lines and in setting up connections from lines of remote semi-automatic exchanges.

Another object is to provide distributing apparatus at a semi-automatic operator's switchboard, which operates in conjunction with sender selectors for connecting the operator's equipment automatically with any sender which has been selected by a sender selector so that the operator may ascertain the desired number and operate a sender to control the automatic switches to set up the desired connection.

A further object of the invention is the production of suitable arrangements, effective in connection with calls set up in a remote exchange by an operator over an operating trunk, controlled from the operating point over the operating trunk to disconnect the operating trunk from the established connection and to place such connection under the control of the calling subscriber without momentarily opening the setting circuit of the switches, as this would result in a failure of the ringing equipment in a reverting call.

This object is accomplished by providing a differential relay with one winding connected in each leg of the simplex operating circuit together with means in the centralized operating exchange for unbalancing the simplex circuit to switch the connection through by operating the differential relay at the correct time.

A further object of the invention is to produce suitable arrangements whereby the release of the connection in the remote exchange is left under the control of the calling subscriber until an idle sender has been actually selected in the centralized operating exchange and for then temporarily removing the control of the release from the calling

subscriber and for holding the connection in a locked condition until the desired number has been set up and the sender has completed its sending operation. This latter object is accomplished by means of a counting device 55 under the control of the above-mentioned differential relay and in connection with suitable cooperating circuit arrangements in the centralized exchange.

A further object of the invention is the provision of practical and economical circuit arrangements for putting a system of the foregoing character into successful operation.

Other objects and features of the invention 65 will appear as the description which is to follow is perused.

General description

Referring now to the drawing comprising 70 Figs. 1-5, they show by means of the usual circuit diagrams, a sufficient amount of apparatus in a telephone system embodying the features of the invention to enable the same to be understood.

Referring now particularly to Fig. 1, this drawing shows equipment located in a remotely controlled semi-automatic exchange, connected with the control point by the single operating trunk shown in the lower right hand corner of the drawing. The equipment shown includes the line of substation T1, which terminates at the exchange in the automatic line switch LS1, which has access to 75 selectors among which is selector switch S1. The trunk circuit TC1 is associated with the trunk line leading to selector S1, and it is through this trunk circuit that the trunk 80 finder TF, in which the operating trunk terminates, is associated with the trunk line to enable the automatic switches to be controlled to set up connections.

Referring now particularly to Fig. 2, this drawing shows apparatus located in a semi-automatic exchange which is the control 85 point from which several outlying remotely-controlled semi-automatic exchanges, such as the one shown in Fig. 1, may be controlled. The equipment shown in Fig. 2 includes a line of sub-station T2, which terminates at the ex- 90 95 100

change in the line switch LS2, having access to first selectors, one of which is the selector S2. The trunk circuit TC2 with which the sender selector SS1 is associated is inserted in the trunk line between the bank of the line switches and selector S2 for the purpose of enabling an association to be made between the trunk line and an idle sender so that the operator can control the automatic switches to set up desired connections. The operating trunk incoming from the remote exchange shown in Fig. 1 terminates in the lower left hand corner of Fig. 2 in the repeating coil and associated relays which operate with the sender selector SS2 to associate the operating trunk with an idle sender when a call arrives over the operating trunk.

The apparatus shown in Figs. 3, 4 and 5, includes the operator's sender-control key set and associated relays, shown in Fig. 3, and one of the four senders shown in the remaining portion of Fig. 3 and in Figs. 4 and 5. The portion of the sender shown in Fig. 3 includes the relays 311—314, while the registering portion is shown in Fig. 4 and the sending portion is shown in Fig. 5. The layout of apparatus is such that each semi-automatic operator is provided with four senders, the sender selectors, Fig. 2, which are usually 25-position mechanisms, have access to senders of several operators.

Detailed description

The apparatus having been described generally in this manner, a detailed description of its operation will now be given. For this purpose it will be assumed the subscriber at sub-station T2, Fig. 2, desires a connection to be set up from his line to the line of another local subscriber whose number is, for example, 5326.

Connection set up in centralized exchange

When the receiver is removed at station T2, the line switch LS2, the circuit of which are not shown, operates in the usual manner to select an idle trunk, which trunk, it will be assumed, is the one comprising conductors 214—216. When this trunk is seized, line relay 201 thereof operates over the calling line and at its upper armature places ground on the release trunk conductor 215 so as to guard the trunk line from intrusion and to maintain the line switch LS2 operated. At its inner lower armature, relay 201 closes a circuit for switching relay 203 in series with the associated operating magnet of the sender selector SS1. At the same time, relay 201, at its lower armature, connects test wiper 206 to the junction of relay 203 and the operating magnet, with the result that the sender selector searches for an idle trunk in the usual manner.

Sender selection

Assuming that the trunk line comprising conductors 209—213 and extending to the sender shown in Figs. 3—5 is the one found to be idle, switching relay 203, which is short circuited as long as a ground potential is encountered by test wiper 206, energizes in series with the associated operating magnet, which magnet does not operate at this time on account of the relatively high resistance of relay 203. At its inner lower armature, relay 203 disconnects test wiper 206 from the junction of the winding of relay 203 and the operating magnet and connects the wiper to ground, thereby placing a guarding and holding potential on conductor 211. At its remaining contacts, relay 203 connects up the remaining wipers on the switch SS1. As a result of impulse wiper 207 being connected up at the middle upper armature of relay 203, the upper winding of line relay 221 of the selector S2 is energized over the upper talking conductor and over conductor 213 extending to the sender across Figs. 3 and 4 to ground through contacts of the interrupter I in Fig. 5. Upon operating, relay 221 closes a circuit for release relay 222, which operates to prepare the switch for operation.

In the selected sender, relay 311 operates over the grounded release-trunk conductor 211 and through contacts of relay 312 and at its lower armature disconnects the corresponding test conductor from ground and extends it to the #1 connecting relay 308. This is preparatory to enabling the distributor D to stop on a contact associated with the #1 sender and operate the #1 connecting relay so as to connect the #1 sender with the operator's equipment. At its upper armature, relay 311 places ground on the associated start operating slow-acting relay 304 through contacts of relays 305—308. Relay 304 closes a circuit for the associated relay 303, which relay operates and starts the hunting action of the distributor D by connecting test wiper 325 to stepping magnet 324 through the self-interrupting contacts of the stepping magnet. At its two upper armatures relay 303 disconnects common conductors 326 and 327 from the operator's head-set and connects the conductor 327 through the associated condenser to the differential tone generating relay. Each time relay 302 pulls up and closes a circuit for its upper winding in parallel with its lower winding, it falls back due to the differential relation between its two windings, thereby generating a tone current which is impressed on conductor 327 through the associated condenser. This tone current is not sent back to the calling line for the time being.

The test wiper 325 of the distributor D encounters a ground potential on the test contact of each sender not in calling condition

owing to the fact that the relay corresponding to 311 in each sender not in a calling condition is deenergized and has a ground potential placed on the corresponding test conductor at its lower armature.

When the distributor D arrives on a contact associated with the calling sender, the first contact or the fourth contact, the stepping operation ceases due to the absence of a direct ground potential on the test conductor and a circuit is closed for relay 308 through test wiper 325 and the lower armature, operated of relay 311, from battery through stepping magnet 324 and the lower contacts of relay 303. Operating magnet 324 does not operatively energize in series with relay 308 owing to the relatively high resistance of the latter. When relay 308 operates, it connects at certain of its lower armatures the six conductors associated with the operator's key set to the corresponding conductors of the sender; it closes a locking circuit for itself at its inner lower armature in multiple with the lower contacts of relay 303; it lights the call lamp associated with the operator's key set at its upper armature; connects up the conductors 209 and 210 at its intermediate upper armatures to the common conductors 326 and 327; and at its upper armature it opens the circuit of slow-acting relay 304. During the time required for relay 304 to fall back after its circuit is opened, the tone generated by the differential tone relay 302 is heard by the calling subscriber, who is informed thereby that he may now give the desired number to the operator.

Relay 304 falls back shortly and opens the circuit of relay 303 in addition to stopping the generating of tone current, whereupon relay 303 falls back and connects conductors 326 and 327 to the operator's head-set. At the time this connection is made, the operator's head-set is short circuited by contacts of relay 301 so that the charge on the associated talking condenser is equalized with the potential difference across conductors 326 and 327 so as to shield the operator from disagreeable noises in her head-set. Relay 301 falls back an instant later and places the operator into communication with the calling subscriber.

Registration of desired number

Upon hearing the number desired by the calling subscriber, which number, as hereinbefore assumed is 5326, the operator depressed the digit keys of her key set for the respective digits of the number. It will be noted that the four conductors associated with the digit keys are labeled A, B, C, and D. The operation of a given key results in the grounding of one or more of these conductors. As an aid in reading the drawing, the conductors grounded responsive to the opera-

tion of each key have been noted in parenthesis above each key.

When the operator depresses the #5 key to set up the first digit 5, the B and D conductors are grounded, operating relays B1 and D1 of the thousands register Fig. 4, relay 412 being operated at this time from the grounded release trunk conductor 211 through contact of release relay 314 and the inner upper contacts of the transfer relay 411. Upon operating, relays B1 and D1 lock themselves to conductor 323 through transfer relay 411, but relay 411 does not operate until the initial circuit of these relays is opened, being short circuited until this happens.

When the key is released, relay 411 operates in series with relays B1 and D1 (which latter relays remain operated) and at its inner upper armature it disconnects the connecting relay 412, whereupon relays A1—D1 are disconnected from the conductors A—D. At its upper armature, relay 411 places ground on conductor 322 through contacts of relay 414, operating relay 313, Fig. 3 to open a point in the switch through circuit to be hereinafter described and to place a multiple ground connection on release-trunk conductor 211. At its middle upper armature, relay 411 extends a ground potential to the relays of the hundreds register, operating relay 422 to connect the conductors A, B, C, and D, to the relays A2, B2, C2, and D2, respectively.

Now, when the operator depresses the #3 key to register the hundreds digit 3, conductors A and D are grounded, operating relays A2 and D2. These relays lock up in series with relay 423, which remains short circuited as long as the key is depressed and operates as soon as the key is released. Relay 423, in addition to extending a ground potential to the tens register to cause relay 432 to operate, disconnects relay 422 and places a further multiple ground connection on conductor 322.

When the tens digit 2 is registered by depression of the #2 key, relays A3 and C3 are operated over conductors A and C, whereupon they lock up in series with relay 431, which relay operates when the key is released and transfers the control to the units register by releasing relay 432 and operating relay 442. A further multiple ground connection is made to conductor 322 at the upper armature of relay 431.

When the units digit 6 is registered by the depression of the #6 key, relays C4 and D4 operate over conductors C and D and lock up in series with relay 441, which operates when the key is released to open the circuit of relay 442 and place a still further multiple ground connection on conductor 322.

Retransmission of number

Having finished setting up the number, the operator depresses the start key, whereupon start relay 312 is operated through con-

tacts of relay 308 and through the lower winding of relay 311 and closes a locking circuit for itself to conductor 211 at its inner upper armature, at the same time disconnecting the upper winding of relay 311. Relay 311 remains operated through its lower winding until the start key is released whereupon it falls back and opens the circuit of relay 308, at the same time replacing ground 10 on the associated contacts in the bank of wiper 325 of the distributor D. Relay 308 falls back and disconnects wiper 325 from the associated operating magnet, at the same time severing all connection between the 15 operator's common equipment and the sender #1 and closing the associated point in the chain circuit of start relay 304 so as to enable the distributor D to operate again to connect the operator's head-set to another 20 sender which may have been taken for use in the meantime.

As a further result of the operation of start relay 312, it prepares the switch-through circuit, to be hereinafter described, 25 at its upper armature, and at its middle armature it places ground from the inner contacts of relay 313 on start conductor 321 so as to start the stepping action of the counting switch CS, Fig. 5, under the control of the 30 marginal stepping relay 501 associated with the interrupter I.

It may be pointed out at this time that the interrupter I is first started into operation upon the seizure of the sender when the 35 ground potential is placed on release-trunk conductor 211. This results in a closure of a circuit through the magnet winding of the interrupter I and through the marginal stepping relay 501 in series. Relay 501 does not 40 operate in series with the magnet winding of the interrupter I, but upon the energization of this magnet winding, the weighted pendulum is drawn over to the right, short circuiting the magnet winding of the interrupter whereupon the interrupter magnet de- 45 energizes and the stepping relay 501 energizes. When the pendulum swings to the left, it again includes the magnet winding of the interrupter in circuit, whereupon relay 501 falls back. As the interrupter I continues to operate, the impulse relay 501 is 50 operated each time the pendulum swings to the right, and the interrupter contacts of the interrupter I are opened each time the 55 pendulum swings to the left.

Now, the operation of the interrupter I is ineffective, and the operation of stepping relay 501 is ineffective likewise until start conductor 321 is grounded as above described 60 upon the depression of the start key by the operator, from which time each deenergization of stepping relay 501 results in an energization of the operating magnet of the counting switch CS from conductor 321 65 through contacts of stop relay 503. The

wipers 504 and 505 on the counting switch CS are advanced only upon the back stroke of the operating magnet, and they consequently remain in the position shown upon the first energization of the magnet. When 70 the pendulum of the interrupter I swings to the right and opens the operating-magnet circuit by energizing stepping relay 501, the operating magnet falls back and advances the wipers 504 and 505 one step, whereupon pick-up wiper 504 encounters a grounded contact, closing a circuit for pick-up relay 502. Pick-up relay 502 operates and prepares a locking circuit for stop relay 503 at its lower armature; places a further multiple ground connection on conductor 322 at its upper armature; and at its inner upper armature it removes one ground connection from the outgoing impulse conductor 213, leaving the conductor grounded only 75 through the contacts of the interrupter I.

Now, with the circuit in this condition, each time the pendulum of the interrupter I swings to the left, it sends an "impulse" 80 by removing ground from conductor 213 to de-energize the line relay of the selector S1, Fig. 1. The operating magnet is reoperated by the deenergization of stepping relay 501 so that each time the pendulum swings to the right relay 501 reoperates and 85 drops back the operating magnet to advance wipers 504 and 505 another step.

When the wipers of the counting switch are advanced again at the end of the transmission of the impulse, wiper 505 encounters the bank contact in which the first stop conductor terminates, which stop conductor is grounded only in case the digit being transmitted is the digit 1. The digit being transmitted in this case is the digit 5, stored 90 on the thousands register Th, Fig. 4, from which it follows that the #5 conductor is grounded instead of the #1 conductor. The #5 conductor is grounded at this time through the lower armature, normal, of transfer relay 414, Fig. 4, right hand armature, normal, of relay A1, outer armature, operated, of relay B1, middle armature, normal, of relay C1, and the associated armature, operated, of relay D1. That being 95 the case, the sending operation continues and the advance of the counting switch CS continues until five impulses have been sent by the interrupter I over the outgoing control circuit. At the end of the fifth impulse wipers 504 and 505 are advanced again and wiper 505 closes a circuit for stop relay 503 when it 100 encounters the bank contact in which the grounded stop conductor #5 terminates. Relay 503 operates and locks itself through the lower contacts of relay 502; closes a restoring circuit for the counting switch CS at its inner upper armature; stops the impulse transmission by shunting the sending contacts of the interrupter I at another upper 105 110 115 120 125 130

armature; places a further multiple ground connection on conductor 322 at still another armature; and at its upper-most armature it disconnects the operating magnet from the impulse circuit controlled by stepping relay 501.

Responsive to the closure of the restoring circuit of the counting switch CS at the inner upper contacts of relay 503, the self-interrupting operating magnet operates rapidly in a buzzer-like manner and the wipers 504 and 505 are advanced until they stand in the position shown in the drawing, whereupon the action ceases due to the fact that the normal contact in the bank of wiper 504 is ungrounded. At this time the circuit of slow-acting pick-up relay 502 is opened, with the result that the relay falls back shortly and opens the locking circuit of relay 503, which relay shortly falls back to start the transmission of the hundreds digit 3.

When the circuit of stop relay 503 is first closed at the end of the transmission of the thousands digit, a parallel circuit is closed over conductor 401 and through contacts of relay 414 for relay 413. Relay 413 operates and locks itself to conductor 323 in series with relay 414, which latter relay remains short circuited until the locking circuit of relay 503 is opened by relay 502, whereupon relay 414 energizes in series with relay 413 and transfers conductor 401 to relay 423 of the hundreds register.

The sending operation proceeds for the second digit in the same manner as described in connection with the first digit and is terminated at the end of the transmission of the third impulse upon the energization of stop relay 503, when wiper 505 encounters the bank contact in which stop conductor 3 terminates. The stop conductor #3 is grounded at this time through contacts of relays 414 and 424 and through contacts of the operated relays A2 and D2, in addition to the contacts of the unoperated relays B2 and C2.

Relay 423 is energized at this time in multiple with the stop relay and locks itself in series with relay 424, which latter relay operates, when the circuit of the stop relay is opened and transfers conductor 401 to relay 433 of the tens register. The stopping ground potential is shifted at the lower contact of relay 424 to the register relays of the tens register.

When the retransmission of the tens digit takes place, the operation is the same as described hereinbefore until stop relay 503 operates at the end of the second interruption in the outgoing control circuit when wiper 505 encounters the bank contact in which stop conductor #2 terminates, stop conductor #2 being grounded at this time through contact of the operated relays A3 and C3 and contacts of the non-operated relay B3. Relays 433 and 434 are operated in a manner

similar to relays 423 and 424 to transfer the control to the unit register.

The transmission of the units digit 6 next takes place and is terminated upon the energization of stop relay 503 at the end of the 6th interruption in the outgoing control circuit when wiper 505 lands upon the bank contact in which stop conductor 6 terminates, stop conductor 6 being grounded at this time through contacts of the non-operated relays A4 and B4 and contacts of the operated relays C4 and D4.

Freeing the sender

It will be noted that each of the relays 414, 424, 434, and 444, upon operating removes ground at one point from the multiply-grounded conductor 322. Now, when relay 444 operates upon the opening of the circuit of slow-acting stop relay 503, when pick-up relay 502 falls back at the end of the unit digits, it leaves conductor 322 grounded only at the contacts of stop relay 503. Now, when relay 503 falls back at this time conductor 322 is ungrounded at all points and relay 313, Fig. 3, falls back as a result. Relay 313 removes ground from start conductor 321 at its inner armature and at its upper armature it removes ground at one point from conductor 211 and closes the switch-through circuit through contacts of the operated relay 312 and over conductor 212. This circuit includes wiper 205 of the sender selector SS1, Fig. 2, the inner upper contacts of switching relay 203, and the switch-through relay 202. Relay 202 operates and locks itself to release-trunk conductor 215 at its inner upper contacts, and at its upper and lower armatures it disconnects the incoming conductors 214 and 216 from the line relay 201 and extends them to the corresponding conductors of the connection established through the selector S2. As a result of this, line relay 201 falls back, followed by the falling back of relay 203 to disconnect the wipers of the sender selector SS1, to free the sender. The established connection is now held up over the line of sub-station C2.

When the sender is freed, the removal of the ground potential from conductor 211 results in the de-energization of relay 312, Fig. 3, and in the deenergization of relays 411, 413, and 414, Fig. 4. As a result of the deenergization of relay 411, relays 421, 423, and 424 fall back and the deenergization of relays 431, 433, and 434 follows, from which follows the de-energization of relays 441, 443, and 444. The operation of the interrupter I ceases as a result of the removal of the ground potential from conductor 211.

The sender is now at normal and may be seized again for use in another call.

Setting the switches

The response of the automatic switching

mechanism to the impulse trains retransmitted by the sender will now be considered. Returning now to the point at which the first series of impulses (interruptions) is transmitted to the upper winding of line relay 221 of the selector S2, each time the circuit of this upper winding is opened at the contacts of the interrupter I, Fig. 5, line relay 221 falls back and closes a circuit for the associated vertical magnet through the lower armature, operated, of relay 222 and the winding of series relay 223. By the operation of the vertical magnet the wipers 226—228 are raised step by step until they 15 come to rest opposite the fifth level of bank contacts, the digit received being the digit 5. Relay 223 energizes in series with the vertical magnet when the first impulse is received, and, being slow acting remains operated 20 throughout the series of impulses. Upon operating, relay 223 prepares a circuit from the grounded release trunk conductor 215 for relay 224, which is closed as soon as the associated off-normal contacts have closed 25 upon the first vertical step. Upon operating, relay 224 prepares a circuit for the rotary magnet at its lower armature and its upper armature closes a locking circuit for itself from the inner lower contacts of relay 228 and including the associated rotary-magnet interrupter contacts and the associated off-normal contacts.

At the end of the vertical movement, relay 223 falls back and closes the rotary magnet circuit, whereupon the rotary magnet operates and advances the wipers 226—228 one step. If the trunk line terminating in the first set of bank contacts is idle, switching relay 225 operates in series with relay 224 35 and seizes the trunk. Assuming, however, that trunk line is busy, relay 225 is short circuited by the ground potential encountered on the test contact by test wiper 227 and does 40 not operate. Relay 224 operates again through test wiper 227, and the rotary magnet is reoperated to advance the wipers another step.

This alternate operation of stepping relay 50 224 and the associated rotary magnet continues until an idle trunk line is reached, whereupon the rotary movement stops and relay 225 energizes and switches the connection through to the idle trunk. Relay 224 55 does not operate at this time owing to the relatively high resistance of switching relay 225.

When the connection is switched through 60 to the idle trunk, the switch in which this trunk line terminates is prepared for operation in the usual manner and a ground potential is placed by the release relay thereof (not shown) on the associated release trunk conductor. Line relay 221 falls back as a 65 result of the operation of relay 225 and the

slow acting release relay 222 falls back a moment later.

Responsive to the transmission of the remaining digits, the remaining portion of the connection to the called line is set up in the well-known manner.

The established connection is held over the calling line and over the two local talking conductors in series after the connection has been switched through upon the operation 75 of the switch through relay 202 of the trunk circuit TC2.

Release of connection

The conversation between the called subscriber and the calling subscriber takes place 80 in the usual manner when the called subscriber responds, and the connection releases in the well-known manner when the subscriber at substation C2 replaces his receiver. The release of the switches LS2 and S2, as well as the trunk circuit TC2, it may be 85 pointed out, takes place when the ground potential is removed from the release trunk conductor of the established connection by the final switch. When this occurs, switching relay 225 of the selector S2 and switch-through relay 202 of the trunk circuit TC2 both fall back. The switching relay 225 closes the circuit of the associated release magnet at its inner lower contacts, through 90 the lower contacts of relays 221 and 222 and through the associated off-normal contacts. By the operation of the release magnet the 95 mechanism of the switch is restored to its normal position, whereupon the off-normal contacts associated with the release magnet open the circuit thereof.

It will now be assumed that the subscriber at substation T1, Fig. 1, desires to converse 100 with another subscriber whose lines terminates in the same remote exchange and whose number is, for example, 914.

Connection set up in remote exchange

When the receiver is removed at substation 110 T1, the line switch LS1 operates in the usual manner to select an idle trunk, the trunk comprising conductors 112—114, for example. When this trunk is seized, line relay 102 energizes over the calling line and places ground on the first-level start conductor 119 at its upper armature. At its lower contacts relay 102 removes the guarding potential from the associated test contact in the bank of the trunk 115 finder TF and prepares a holding circuit for relay 128.

When the first-level start conductor 119 is 120 grounded as above pointed out, a circuit is established through the associated resistance 125 and over conductor 120 for start relay 129 through contacts of relay 127 and contacts of the release magnet. Start relay 129 operates and closes at its second armature from the bottom a circuit through the contacts of the 130

vertical magnet, contacts of relay 131, contacts of the rotary magnet and its own lower contacts for stepping relay 130. Relay 130 operates and completes a circuit for the vertical magnet at its lower contacts, whereupon the vertical magnet responds by raising the wipers 121-136 and the test wiper 136 one step. The vertical magnet also opens the initial circuit of stepping relay 130. In case there is no call waiting on the first level, this results in a deenergization of stepping relay 130 and in a further operation of the vertical magnet. In this case, however, the calling trunk is reached from the first level of the finder and test wiper 136 encounters a ground potential on the first level-test contact over the start conductor 119 with the result that relay 130 remains operated notwithstanding the opening of the vertical magnet interrupter contacts. The new circuit includes normally closed contacts controlled by the inner lower armature of relay 131, the lower winding of relay 131, vertical test wiper 136 on its first level contact, and the grounded start conductor 119. Relay 131 operates in series with relay 130 and closes a locking circuit for its upper winding through its upper contacts at relays 129 and 128. Relay 131, at its lower armature, transfers the magnet-operating circuit from the vertical magnet to the rotary magnet; while at its inner lower armature, it closes transfer relay 130 from the vertical test wiper 136 to rotary test wiper 125. Relay 130 is now held energized in a locking circuit including its own inner lower contacts and the middle lower contacts of relay 129.

When the rotary magnet operates, it advances the wipers 121-126 one step into engagement with the first set of contacts in the first level, and it opens the circuit of relay 130. Relay 130 thereupon falls back and opens the circuit of the rotary magnet and a further point in its own circuit. The further operation depends upon whether the trunk line TC1 terminates in the first set of contacts in the level or in some other set. It will be assumed that the latter is the case. When rotary magnet 130 falls back, it closes a circuit for relay 130 at its interrupter contacts through the third armature from the bottom of relay 131, to ground through test wiper 125 and the grounded test contact on which it is standing. It will be noted that the presence of this ground potential is the only thing which prevents the lower winding of relay 128 from energizing through the inner lower contact of relay 129 in series with relay 130. Relay 130 reoperates and again closes a locking circuit for itself at its inner lower armature, at the same time again operating the rotary magnet to bring about a further advance of the wipers of the switch.

This stepping operation of the trunk finder TF continues until the wipers land upon the contacts associated with the trunk circuit

TC1, whereupon the action ceases due to the fact that there is no ground potential on the test contact in the bank of wiper 125 because line relay 102 is operated. In this case, relay 130 does not operate through the test wiper again and relay 128 energizes in series with relay 130, but relay 130 does not operate again owing to the relatively high resistance of the lower winding of relay 128. When relay 128 operates, it closes a locking circuit for itself at its inner upper contacts and over test wiper 124 and the contact on which it is standing and through the lower armature of line relay 102. At its middle armature, relay 126 opens the circuit of relay 131, and at its lower armature it closes a circuit for relay 127. Relay 127 operates and at its inner upper armature opens the circuit of start relay 129, whereupon this relay falls back. At its three upper armatures and at its lower armature, relay 127 connects up wipers 121-123 and 126.

As a further result of its operation, above described, relay 128 at its upper armature connects impulse relay 128 to the conductors of the operating trunk through the windings of differential relay 134. When this occurs, impulse relay 132 energizes over the lower conductor of the operating trunk, through the repeating coil windings on either end of the operating trunk, and in series with relay 241 associated with sender selector SS2, Fig. 2, through contacts of relay 243. Upon operating, relay 132 extends a ground potential over the associated impulse conductor through contacts of relay 127 and over wiper 123 to the upper winding of line relay 104 of the selector S1 by way of contacts of relay 108. Relay 104 operates, followed by the energization of relay 105 to prepare the selector S1 for operation.

Differential relay 132 operates, because current is flowing through only one winding, and closes a circuit for the upper winding of two-step relay 133, which relay operates through its first step.

In the centralized exchange, relay 241, upon operating over the operating trunk as above mentioned, closes at its inner lower and middle lower armatures circuits for causing the sender selector SS2 to advance under the control of test wiper 249 in search of an idle sender in the manner hereinbefore described in connection with the sender selector SS1. When an idle sender is found, the one for example shown in Figs. 3-5 and reached by way of conductors 209-213, switching relay 245 operates, and, in addition to grounding test wiper 249 at its inner lower armature, connects up wipers 247, 250, and 251 at its remaining armatures.

Upon referring again to Fig. 1, it will be noted that the release of the connection established to the idle sender is under the control of the subscriber at substation T1 and that should he hang up his receiver at this

- stage before communicating with the operator, the connection would release responsive to the falling back of line relay 102 of the trunk circuit TC1, which would be followed by the deenergization of relays 128, 127, and 132—134 of the trunk finder TF and the release of the trunk finder. In the sender selector SS2, Fig. 2, relay 245 would fall back as a result of the deenergization of relay 241. This is mentioned at this point owing to the fact that this condition will be changed as will be pointed out hereinafter. When wiper 250 is connected up, relay 244 energizes through this wiper from ground on impulse conductor 213, which is grounded through contacts at relay 502 of the sender. Relay 244 locks itself energized and transfers the incoming impulse conductors to wiper 250, at the same time closing a local circuit for relay 241 through resistance 246. Current now flows from the grounded conductor 213 and through wiper 250 over both conductors of the operating trunk, whereupon differential relay 134, Fig. 1, falls back and opens the initial circuit of the upper winding of relay 133, whereupon, the lower winding, which has been short circuited heretofore, energizes in series with the upper winding and operates the relay through its second step. At this time, relay 133 at its lower armature, places the associated resistance in shunt of the talking condenser connecting the left-hand repeating coil windings. This establishes a parallel circuit for line relay 102 so as to hold this relay energized independent of the calling party until the connection has been set up.
- Responsive to the grounding of release trunk conductor 211 of the sender through test wiper 249, relay 311, Fig. 3, operates as hereinbefore described to cause the operator's equipment to become connected with the selected sender, and the interrupter I, Fig. 5, begins the hereinbefore-described operation. It will be remembered that the energization of relay 311 is followed by the energization of relays 304 and 303 and by the step-by-step operation of the distributor D which results in the distributor D landing upon the contact leading through the lower armature of the operated relay 311 to the #1 connecting relay 308, and that the resulting operation of relay 308 is followed by the deenergization of relays 304 and 303 whereupon the connection is completed from the calling line to the operator's telephone after a momentary application of the current has been made to the calling line to inform the calling subscriber that the operator is waiting for the number.

After learning the desired number from the subscriber, which number as hereinbefore assumed is 914, the operator depresses the #9 key, the #1 key and the #4 key, one after the other, with the result that the digits

are stored on the thousands, hundreds and tens registers, Fig. 4, in a manner similar to that described in connection with the call from the subscriber at substation T2.

In the thousands register, the digit 9 is stored by the operation of relay C1; in the hundreds register the digit 1 is stored by the operation of relays A2 and B2; and in the tens register the digit 4 is stored by the operation of relays B3 and C3. It will be recalled that relay 411 operates when the first digit is stored; that relay 421 operates when the second digit is stored; and that relay 431 operates when the third digit is stored. When these three relays are operated, conductor 322 is grounded at three points. Relay 313, of course, is operated upon the first application of ground potential to conductor 322 when the digit 9 is stored.

Having set up the three digits in the called number, the operator depresses the start key, Fig. 3, operating relay 312 to start the sender to operate and to disconnect the operator from the sender by releasing relay 311 when the start key is closed. The sending apparatus of Fig. 5 now operates responsive to the ground potential on start conductor 321 and retransmits the stored digits 9, 1, and 4 in the hereinbefore described manner. It will be remembered that relay 413 of the thousands register, Fig. 4, operates upon the first energization of stop relay 503, Fig. 5, at the end of the first digit and that relay 414 operates a moment later when the circuit of relay 503 is opened upon the falling back of relay 502, transferring the control to the hundreds register; that the relays 423 and 424 operate at the end of the second digit; and that the relays 433 and 434 operate at the end of the third digit.

Upon the operation of relay 434 at the end of the third and last digit 4, the ground potential is removed at the last point from conductor 322. Relay 313 falls back and closes the prepared switch-through circuit (through the upper contacts of relay 312 and over conductor 212) for switch-through relay 243, of the sender selector SS2, by way of wiper 248 and contacts of relay 245. Relay 243 operates and locks itself through contacts of relay 241 and it opens the circuit of relay 244 at its inner lower armature, whereupon relay 244 falls back and transfers the upper conductor of the operating trunk back to relay 241 and again opens the lower conductor. When this occurs, differential relay 134, Fig. 1, pulls up again and, this time closes a circuit through contacts at relays 133 and 127, and through wiper 122 for switch-through relay 103.

Relay 103 operates and locks itself to the associated grounded release conductor 113 at its inner upper armature, and at its upper and lower contacts it switches the conductors

112 and 114 straight through to the corresponding conductors of the selector S1, at the same time disconnecting conductors 112 and 114 from the line relay 102. Relay 102 now 5 falls back and opens the holding circuit through the upper winding of relay 128, whereupon relay 128 falls back and disconnects wiper 126 at its lower armature, while at its middle upper armature it closes a circuit for the associated release magnet through contacts of relay 129 and off-normal contacts. The release magnet operates and restores the finder to its normal position in the usual manner, whereupon the release 10 magnet circuit is opened at the associated off-normal contacts. The contacts of the release magnet maintain start relay 129 disconnected during the releasing operation. It will be noted that the circuit for maintaining 15 relay 129 disconnected after the finder has operated is taken through contacts of relay 127, which is a slow acting relay and that the release magnet circuit is closed at the same time that the circuit of relay 127 is opened.

20 Due to the fact that relay 127 is slow acting the release magnet has time to energize and disconnect relay 129 at a further point before the slow acting relay 127 falls back and closes the associated point in the circuit of 25 relay 129. This is of utility in case the start conductor is grounded at the time the release occurs, as it prevents the finder from trying to test while it is releasing. Relays 132-134 fall back when relay 128 restores. As a result of the opening of the upper contacts of 30 relay 128, line relay 241, Fig. 2, falls back and opens the circuit of relays 243 and 245, which relays fall back and restore the associated circuit connections to normal.

35 The operating trunk may now be used in connection with any subsequent call.

40 The connection set up through the line switch LS1 and the selector S1 is released in the usual manner when the calling subscriber replaces his receiver after conversation. The 45 release of the selector upon the falling back of relay 108 is brought about by the energization of the release magnet of the selector when ground potential is removed from the 50 release trunk conductor of the established connection, and the locked up switch-through relay 103 falls back at the same time.

55 Referring again to Figs. 3 and 4, it may be pointed out that the operator can release a partial registration by operating the release key shown in the lower left hand corner of Fig. 3 in case she discovers that she has made an error. When the release key is operated, relay 314 pulls up and disconnects the 60 grounded conductor 211 from conductor 323, permitting the registering apparatus of Fig. 4 to restore to normal. Following this, the operator permits the release key to restore and proceeds to set up the number by operating 65 her number keys in the usual manner.

In case a call comes into the operator and no response is secured to the momentary application of tone current and to a challenge by the operator, she may cause the connection to be switched through to the first selector 70 and thereby free the sending equipment, by operating her start key without first setting up a number. As an alternative, the operator may set up a predetermined number and cause the call to be trunked to a special position especially equipped for handling "false" 75 calls. This latter arrangement is usually preferable, as it enables the attendant at the special position to make proper record of false calls so that their cause may be located 80 and remedied.

What is claimed is:

1. In a multi-office semi-automatic telephone system, a first office and a second office, operator-controlled senders located in the first office, and means including local trunks and inter-office trunks whereby the said senders are used to control the operation of the 85 automatic switches to set up connections local to both offices.

2. In a telephone system wherein connections are set up through automatic switching mechanism controlled from an operator's switchboard through the intermediary of register senders at such switchboard, operator's 90 common equipment, means for seizing said register senders at random as calls are initiated, and means for automatically connecting the associated common equipment with any seized sender.

3. In a telephone system wherein register senders are provided for controlling automatic switches, an operator's switchboard, a plurality of register senders at said switchboard accessible to calling lines, a distributing device at said switchboard having access to each of said senders, and means responsive to the seizure of one of said senders for advancing said distributing device and for bringing it to rest in association with the 100 seized sender.

4. In a telephone system wherein register senders are provided for controlling automatic switches, an operator's switchboard, a plurality of register senders at said switchboard accessible to calling lines, a distributing device at said switchboard having access to each of said senders, means responsive to the seizure of one of said senders for advancing said distributing device and for bringing it to rest in association with the seized sender, operator's common equipment, a connecting relay associated with each of said senders, and means controlled by said distributing device when it finds a seized 110 sender for operating the connecting relay of such sender to connect the operator's common equipment with the seized sender.

5. In a telephone system, an operator's switchboard, a common talking circuit com- 120

- prising two sections the first of which extends to the operator's telephone, a plurality of individual talking circuits terminating at said switchboard, automatic means for extending connections from subscriber's lines to any one of said individual talking circuits, means including a hunting device responsive to a connection extended to one of said individual talking circuits, for impressing a tone current on the second section of said common talking circuit and for starting said distributor to connect the seized individual talking circuit with the second section of said common talking circuit, and means effective a moment after the said connection is effected for discontinuing the application of tone current to the said second section of the common talking circuit and for uniting the two sections so that the operator may converse with the calling subscriber.
6. In a remotely-controlled semi-automatic exchange system, means responsive to the initiation of a call on a line terminating in a remotely-controlled semi-automatic exchange for extending such line to an automatic directive switch, an operating trunk extending from the remotely controlled exchange to an operating point, means responsive to the said initiation of a call for associating said operating trunk with the said directive switch and for establishing a switch-control circuit over said operating trunk, means including a sending device at the operating point for interrupting the control circuit over said operating trunk to set up a desired connection through said directive switch, and means controlled from the operating point over the control trunk after the connection has been set up for causing a switch-through operation in the semi-automatic exchange and the freeing of the operating trunk thereat, while maintaining a current flow over the control circuit until the switch-through operation has been effected.
7. In a remotely-controlled semi-automatic exchange system, means responsive to the initiation of a call on a line terminating in a remotely controlled semi-automatic exchange for extending such line to an automatic directive switch, a two conductor operating trunk extending from the remotely controlled exchange to an operating point, means responsive to the said initiation of a call for associating said operating trunk with the said directive switch and for establishing a switch-control circuit over said operating trunk, means including a sending device at the operating point for interrupting the control circuit over said operating trunk to set up a desired connection through said directive switch, and means controlled from the operating point over said operating trunk to switch the connection through at the semi-automatic exchange and to free

the associated end of the operating trunk by unbalancing the current flow in the two conductors of the operating trunk.

8. In a remotely-controlled semi-automatic exchange system wherein the switching apparatus in a semi-automatic exchange is controlled over an operating trunk from a control point, the operating trunk being associated successively with trunk lines over which connections are to be set up, means responsive to the association of the operating trunk with a local trunk when a connection is to be set up thereover for establishing an unbalanced current flow over the operating trunk, means at the control point responsive to such unbalanced flow for signalling the operator at the control point.

9. In a remotely-controlled semi-automatic exchange system wherein the switching apparatus in a semi-automatic exchange is controlled over an operating trunk being associated successively with trunk lines over which connections are to be set up, means responsive to the association of the operating trunk with a local trunk when a connection is to be set up thereover for establishing an unbalanced current flow over the operating trunk, means at the control point responsive to such unbalanced flow for signalling the operator at the control point, and means responsive to the extension of the connection from the control trunk to the operator's equipment for balancing the current flow over the operating trunk.

10. In a remotely controlled semi-automatic exchange system wherein the switching apparatus in a semi-automatic exchange is controlled over an operating trunk from a controlled point, the operating trunk being associated successively with trunk lines over which connections are to be set up, means responsive to the association of the operating trunk with a local trunk when a connection is to be set up thereover for establishing an unbalanced current flow over the operating trunk, means at the control point responsive to such unbalanced flow for signalling the operator at the control point, and means responsive to the extension of the connection from the control trunk to the operator's equipment for balancing the current flow over the operating trunk.

11. In a remotely controlled semi-automatic exchange system wherein the switching apparatus in a semi-automatic exchange is controlled over an operating trunk from a controlled point, the operating trunk being associated successively with trunk lines over which connections are to be set up, means responsive to the association of the operating trunk with a local trunk when a connection is to be set up thereover for establishing an

unbalanced current flow over the operating trunk, means at the control point responsive to such unbalanced flow for signalling the operator at the control point, means responsive to the extension of the connection from the control trunk to the operator's equipment for balancing the current flow over the operating trunk, means responsive thereto for removing the release of the connection from under the control of the calling line, and means responsive to a further unbalanced condition of the operating trunk after the control has been exercised from the operating point for switching the connection through from the calling line to the set up connection through the automatic switches and for disassociating the operating trunk from the local trunk line.

12. In a semi-automatic telephone system wherein a remotely controlled semi-automatic exchange is controlled over a two-conductor operating trunk extending between that exchange and an operating point, which trunk is associated with calling lines successively in the semi-automatic exchange, means controlled over the two operating-trunk conductors for setting the switches in the semi-automatic exchange, and means responsive to current flow over one conductor only of the operating trunk for freeing the operating trunk from an established connection.

13. In a semi-automatic telephone system wherein a remotely controlled semi-automatic exchange is controlled over a two-conductor operating trunk extending between that exchange and an operating point, which trunk is associated with the calling lines successively in the semi-automatic exchange, means controlled over the two operating-trunk conductors for setting the switches in the semi-automatic exchange, means for stopping the current flow over one conductor of the operating trunk while permitting the current flow over the other conductor thereof, and means responsive thereto for freeing the operating trunk from the established connection and for switching such connection through and placing it under the control of the calling line.

14. In a multi-office automatic telephone system, a group of register senders located in a first office, operator's setting equipment common to said register senders, means responsive to current flow over one conductor of the line local to said first office or on a calling line local to a second office for associating an idle one of said register senders with the calling line, and means for thereupon associating the operator's common setting equipment with the last named register sender.

15. In a multi-office semi-automatic telephone system, a first office and a second office, automatic switches in each office arranged to extend calling lines directly, register send-

ers in the second office arranged to exercise directive control over said automatic switches, a trunk line connecting said offices, means responsive to a call on a line in the second office for extending a connection to one of said automatic switches and for extending a branch connection directly to an idle one of said register senders, and means responsive to a call on a line in the first office for extending a connection to one of said automatic switches and for extending a branch connection by way of said inter-office trunk line to an idle one of said register senders.

16. In a multi-office semi-automatic telephone system, a first office and a second office, automatic switches in each office arranged to extend calling lines directly, trunk lines in the second office extending to an operator's switchboard, an interoffice trunk line extending from the first office to the second office, means responsive to a call on a line in the second office for extending a connection to one of said automatic switches in the second office and for extending a branch connection directly to an idle one of said trunk lines leading to the operator's switchboard, means responsive to a call on a line in the first office for extending a connection to one of said automatic switches in the first office and for extending a branch connection by way of said interoffice trunk line to an idle one of said trunk lines leading to the operator's switchboard, and means under the control of the operator for operating the automatic switch to which a connection has been extended from a calling line in either case.

17. In a multi-office semi-automatic telephone system, a first office and a second office, automatic switches in each office arranged to extend calling lines directly, trunk lines in the second office extending to an operator's switchboard, an interoffice trunk line extending from the first office to the second office, means responsive to a call on a line in the second office for extending a connection to one of said automatic switches in the second office and for extending a branch connection directly to an idle one of said trunk lines leading to the operator's switchboard, means responsive to a call on the line in the first office for extending a connection to one of said automatic switches in the first office and for extending a branch connection by way of said interoffice trunk line to an idle one of said trunk lines leading to the operator's switchboard, and means for enabling the operator at said switchboard to converse with the subscriber on either of said calling lines over the branch connection and for operating the automatic switch to which the calling line is connected.

18. In a telephone system, an operator's switchboard, a plurality of trunk lines at said operator's switchboard, talking conductors at said switchboard individual to the opera-

tor's headset and common to said trunk lines, means for extending connections from calling subscribers' lines to idle ones of said trunk lines, means for connecting the said 5 headset conductors to any one of said trunk lines, and means for thereupon making a momentary application of tone current to the said headset conductors to inform the calling subscriber on the calling line that he is 10 in communication with the operator.

19. In a semi-automatic telephone system, trunk lines over which telephone connections are set up through the medium of automatic switches, register senders for controlling the 15 automatic switches to set up the said telephone connections, link circuits arranged to interconnect said trunk lines and said register senders, operator's equipment common to said link circuits and including a group of 20 digit keys and a start key, means for setting up a connection between one of said trunk lines and one of said register senders by way of one of said link circuits, means for setting up a connection from the operator's common 25 equipment to the last named link circuit and register sender, said last means including a distributing device having access to each of said register senders, registering means in the connected register sender responsive to 30 successive manipulations of the operator's digit keys for registering the digits of a desired number, means responsive to an operation of the operator's start key for starting the register sender to retransmit digits by 35 way of the connected trunk line to cause the desired connection to be set up by way of automatic switches, and means in the connected link circuit responsive to the release of said start key following its operation for 40 advancing said distributing device to disassociate the operator's common equipment from the link circuit and connected register sender.

20. In a semi-automatic telephone system, 45 trunk lines over which telephone connections are to be set up through the medium of automatic switches, register senders for controlling said automatic switches, operator's common equipment for controlling said register 50 senders including digit keys and the start key, a distributing device associated with the operator's common equipment and having access to all of said register senders, means responsive to a calling condition on any one 55 of said trunk lines for connecting any idle one of said register senders to such trunk line and for operating said distributing device to connect the operator's common equipment to the connected register sender, registering 60 means in the connected register sender responsive to actuations of the operator's digit keys to store digits of a desired telephone number, and means responsive to an operation of said start key for starting the 65 register sender to transmit the stored digits

to the automatic switches by way of said trunk line and to advance said distributing apparatus out of association with the register sender, the advance of the distributing apparatus being dependent upon the release of the start key following its operation.

In witness whereof, I hereunto subscribe my name this 13th day of April, A. D. 1928.

NORMAN H. SAUNDERS.

In witness whereof, I hereunto subscribe my name this 13th day of April, A. D. 1928.
